HOPSON & MASON.

Spring.

No. 94,603.

Patented Sept. 7, 1869.

United States Patent Office.

GEORGE HOPSON AND JOSEPH H. MASON, OF BRIDGEPORT, CONNECTICUT.

Letters Patent No. 94,603, dated September 7, 1869.

IMPROVEMENT IN SPRINGS.

The Schedule referred to in these Letters Patent and making part of the same.

To all whom it may concern:

Be it known that we, **GEORGE HOPSON** and **JOSEPH H. MASON**, of Bridgeport, in the county of Fairfield, and State of Connecticut, have invented certain new and useful Improvements in the Construction of Springs; and we do hereby declare that the following is a full and exact description thereof.

Our invention relates to what are commonly known as elliptic springs, half elliptic, cross-springs, C-springs, and, generally, to all forms of metal springs in which the steel or other elastic material is constructed in separate plates or leaves, mounted face to face, so that one shall support and contribute to the force of the next.

In all springs of this character, it is necessary to provide some means of maintaining the plates or leaves in their proper positions relatively to each other; that is, to prevent their slipping laterally upon each other, or, in other words, to maintain their parallelism. It has long been common to contribute to this result by making, near the ends, a slot or long depression, extending into or through one of the leaves, with a nipple or bead raised on the face of the next, and fitting inside of the slot or groove. As the spring is bent, the plates or leaves of the spring work or slide upon each other a little, which compels the bead to travel forward and back in the slot or groove. It is necessary to make the groove longer than the slot or bead, in order to allow for this motion. We adopt this mode for guiding and keeping the plates in position, and also adopt the previously-known mode of producing such groove and such bead; that is to say, we produce the required long depression by pressure, with a suitable tool, upon one face of a leaf while it is hot, and sufficiently soft to allow of such indentation; and we produce the bead by forcing out the metal while it is held in a hollow die which has a depression adapted to properly mould the bead.

So far as we have yet explained, our construction has been long known and approved.

It will be understood, that in raising the bead, a punch, or tool of somewhat analogous function, is pressed against the opposite face of the leaf, and thus a depression is caused on that side, partially or exactly corresponding to the bead which is raised on the other side. When the plates or leaves are bolted together in their proper relations to form a spring, the beads are on one side, and the grooves, as also all the indentations opposite the beads, are on the opposite sides or faces of the leaves.

In such spring, every leaf or plate is subject, on one face, to a tensile or rending strain—a force tending to divide it asunder on that surface; and the other face

is exposed to a compressive strain—a force tending to contract or crush it together.

In all previous springs of this kind, the bead has been on the compressed side, and the depressions have been on the distended side of each plate. Our improvement consists in reversing this arrangement. We produce the bead on the distended side, and we produce the opposite depression, which forces up the metal for the bead, and also the longer depression, or blind slot, on the opposite face—that is to say, on the face of the plate or leaf which is compressed; in other words, we put the bead on that side of each leaf which is exposed to a tensile strain, and we put the recess on that side which is exposed to a compressive force. This arrangement avoids the dangerous weakening of the spring due to the old construction.

We employ machinery for producing the beads and the sunk recesses in which they traverse, whereby the plates or leaves are treated without distortion; in other words, we produce the grooves, which are generally denominated "blind slots," by forcing into the hot steel of the leaf a rounded punch of the proper form—that is to say, an eighth of an inch in width, about the same in depth, and one inch, or thereabouts, in length—without raising any appreciable swell, or in any way deforming or defacing the opposite face of the leaf; and we produce the bead, which is an elevation of corresponding width and height, but of less length—say three-eighths of an inch in length—by forcing into one face of the leaf a corresponding punch, and raising a sharply-defined bead of the proper dimensions, without appreciably disturbing the contour of the other parts of the leaf.

By our improved arrangement of the depressions and elevations, we not only increase the strength, or rather, avoid the weakening of the spring, as compared with the old arrangement, but also obtain a fair surface on all portions of the spring which are in sight.

The old arrangement produced a depression on the inside surface of the inner leaf or plate of each spring, and, these being very much exposed to the eye, especially on the lower half of the spring, it has been customary to fill such depression with putty. This barbarous procedure, when the putty was covered with paint, produced an imitation of a fair surface. Ours makes a really fair surface. The putty was always liable to be jarred out, and, in any event, contributed nothing to the strength or usefulness of the structure. Our spring is, in every part, effective.

Instead of forcing the punch quite through the leaf, as has been heretofore practised in forcing up the bead, and thus making the bead only a hollow shell, we take care to hold the hot material very effectually by the

machinery, to guard against distortion, and we raise the bead without forcing the punch more than about half way through the thickness of the plate; in other words, the depression takes out no material on the distended side of the spring, but rather increases the material on that side by the presence of the bead there, and the bead, being solid, and strongly connected, is, in effect, a strengthening-rib, and contributes to the strength and stiffness of the spring, for the short length to which the bead extends, without weakening it at any other point.

The sinking of our blind slot cannot contribute to increase the strength of the spring, because there is no corresponding elevation on the opposite face; but we have modified the form of the blind slot, in addition to placing it on the compressed side of the spring, and have thus attained, as we believe, the minimum degree of weakening from this source. Our modified form is rounded in every direction—that is to say, there are no re-entering angles in or about it. The groove is not as deep at each end as at and near the middle. By this form, we avoid the weakening which is due to the sharp angle heretofore left at each end of the slot.

The advantages of our invention over that construction still in common use, in which each slot is cut quite through its leaf or plate, are too obvious to require special remark. Such slotting removes the material on both faces, and the weakening to the spring is obvious, even if the metal is thus punched hot. When, as is usually the case in that method of manufacture, the punching is effected cold, it not only weakens by the removal of the material in the space occupied by the slot, but it weakens by straining and partially cracking the adjacent material. We have, in this specification, confined attention mainly to the comparison of this with the previously-known spring which most nearly resembles it, to wit, that in which there is a blind slot extending only about half way through the plate, and which we have adopted, with the modifications and improvements herein described.

The accompanying drawings form a part of this specification.

Figure 1 represents a longitudinal section of a little more than half of a light elliptic spring. This spring contains only three plates or leaves, and there is, consequently, a smaller number of depressions and elevations than would be required in a spring with more plates, intended for heavy wagons.

Figure 2 is a cross-section on the line S S in fig. 1.

Figure 1^A is a longitudinal section through a portion of a heavy spring, such as is adapted for stout lumber-wagons, railroad-cars, and the like. This figure shows the relative arrangement of the beads and depressions when there are a great number of leaves.

Similar letters of reference indicate corresponding parts in all the figures.

1, 2, 3, &c., represent the successive plates, reinforcing or contributing their force to aid each other in the order of their numbers; that is to say, the first plate, 1, receives the load directly; the second plate, 2, contributes to assist it; the third plate, 3, contributes again, and so on, for any number of plates.

A A are beads, and a a are the corresponding depressions, produced by a punch, or analogous tool, in raising the bead.

It will be understood, as has been above stated, that in the act of producing the bead, the plate is heated and treated by machinery, which holds it very efficiently against distortion, while a properly-rounded punch is forced in on one face, and raises the bead on the opposite face.

C C are the grooves or blind slots. These are produced, by machinery, while the material of the spring is in a heated, and, consequently, soft condition, and is held against distortion, as has been above explained.

The drawings represent the novel parts, with so much of the other parts as seems necessary to explain their relation thereto. The ends of the springs, the centres, and all the details other than the depressions and elevations above referred to, may be constructed and arranged in any approved manner.

We do not claim a spring in which the compressions are sunk only partially through the thickness of the leaf, and are rounded in contour, as we have described; but

We claim as our invention, and desire to secure by Letters Patent—

The within-described improvements in leaf-springs, having the beads on the distended side, and the depressions on the compressed side of each leaf, all as and for the purposes herein set forth.

In testimony whereof, we have hereunto set our names, in presence of two subscribing witnesses.
